HOMOGENIZING APPARATUS

Harry W. Mould, Jr., Buffalo, N.Y., assignor, by mesne assignments, to Liberty National Bank and Trust Company, Buffalo, N.Y., a national banking association

Filed Jan. 23, 1962, Ser. No. 168,197

7 Claims. (Cl. 259—7)

This invention relates to apparatus for blending and emulsifying or homogenizing fluids such as milk, oil, and the like.

The effectiveness and quality of a homogenization or emulsification process is determined by the extent of reduction of particle size, and the ultimate uniformity of particle sizes as brought about by the process.

The most frequently used homogenizing or emulsification process is an open paddle-tank type operation. However this is a batch type process and normally requires a relatively long period of time for completion. Moreover, because of the relatively extended period of time during which a given batch need be subjected to the agitator, the open paddle tank apparatus, not infrequently subjects the fluid being treated to undesirable temperature rises during the blending operation. Moreover, since the agitator employed in the open paddle tank apparatus tends to create a vortex in the fluid which is being blended, the blending action throughout the tank is uneven; the fluid adjacent the vortex gets much greater action than the fluid remote from the vortex. Furthermore because of the batch nature of the open paddle tank process relatively large and cumbersome equipment is required if any production is to be achieved at all.

For these reasons efforts have been made to homogenize or emulsify fluids by continuous flow processes in which the fluid is flowed through a device containing high speed shearing elements which function to agitate and positively reduce the size of particles in the fluid during the passage of the latter through the device.

An object of this invention is to provide an improved continuous-flow homogenizing or emulsifying unit.

Another object of this invention is to provide an improved continuous-flow homogenizing or emulsifying unit wherein the incoming fluid is subjected to a blending operation before passage of the fluid to the shearing elements of the unit.

Another object of the invention is to provide an homogenizing or emulsifying apparatus of the continuous flow type which will be extremely compact. To this end, it is a further object of the invention to provide an homogenizing or emulsifying apparatus of the type described in which the pump for moving the fluid through the apparatus is combined with the shearing mechanism itself.

Still another object of the invention is to provide apparatus of the type described in which the shearing mechanism, the pump and the drive motor for the pump are all built into one self-contained, compact, easily-serviceable, relatively inexpensive unit.

Other objects of the invention will be apparent hereinafter from the specification and from the recital of the appended claims, particularly when read in conjunction with the accompanying drawing.

In the drawing:

FIG. 1 is a part side elevational view, part sectional view of a homogenizing unit made in accordance with one embodiment of this invention;

FIG. 2 is a fragmentary sectional view on an enlarged scale taken along the line 2—2 of FIG. 1 and looking in the direction of the arrows;

FIG. 3 is a longitudinal sectional view on a reduced scale of a modified form of unit made according to the invention and in which a slotted inner rotor is employed

to initially blend the fluid prior to its entry into the shear elements of the unit; and

FIG. 4 is a fragmentary sectional view on an enlarged scale taken along the line 4—4 of FIG. 3 and looking in the direction of the arrows.

Referring now to the drawing by numerals of reference and first to FIGS. 1 and 2, 10 designates the electric drive motor for the unit. Keyed to the armature shaft 11 of this motor is a conical split collet type adaptor or arbor 12. Adaptor 12 has diametrically opposite slots 13 through it which provide two resilient jaws 14. The adaptor supports a shaft 15 which has an enlarged portion 16 at its rear end that has a conical bore which fits over the adaptor. Screws 17, which pass through a flange 18 at the rear 15 of the shaft and which thread into an opposed flange 19 on the adaptor, serve to secure the shaft on the adaptor so that the two rotate together.

Shaft 15 is of reduced diameter forward of its foot portion 16 as denoted at 21. It has a second reduced diameter portion 22 forward of portion 21; and it has a third reduced diameter portion 24 forward of portion 22. It is threaded at its front end 26.

A circular impeller 31 is secured on shaft 15. The impeller 31 is bored and counterbored to receive the shaft 25 15 including the shoulders 23 and 25 formed on the shaft at the junctures of its first and second reduced diameter portions 21 and 22 and of its second and third reduced diameter portions 22 and 24, respectively. The impeller seats against shoulder 23. The outer peripheral surface 30 of the impeller is provided with a plurality of peripherally spaced, axially extending, notches 32 that have sidewalls slightly inclined in a direction opposite to the direction of rotation (see arrow 34, FIG. 2) of the impeller. Slots 32 define impeller blades 33 and provide a primary centrifugal pumping effect upon the rotation of shaft 15.

Integral with the impeller 31 and projecting forwardly therefrom is an annular rotor element 35. The outer peripheral surface of this rotor is at approximately the same radial distance from the axis of shaft 15 as are the bottoms of the grooves 32 in impeller 31, that is, it is approximately in line with the bottoms of the grooves 32. The rotor element 35 has a plurality of peripherally spaced, shallow grooves 36 formed on its inner face. These extend axially from the rear end of the rotor for substantially the full length of the rotor. As shown clearly in FIG. 2, they are substantially rectangular in cross section. Preferably there are thirteen equi-spaced notches 32 in the peripheral surface of impeller 31, and twenty-six equally spaced grooves 36 on the inner peripheral surface of rotor 35. At the rear end of each groove 36 is circular aperture 37 which is drilled radially through the rotor.

Impeller disc 31 and rotor 35 are secured to rotate with shaft 21 by an internally threaded retaining sleeve 41 which is threaded onto the threaded end 26 of shaft 15. Sleeve 41 has a disc or flange 43 integral therewith which has an outside diameter that is less than the inner diameter of rotor element 35.

Interposed between the disc or flange 43 and the rotor 35, and in very close proximity to both is a coaxial annular stator 50. Stator 50 has an axial length slightly greater than the axial length of rotor 35 and extends into an annular recess 51 in the inner face of impeller 31. In its outer peripheral surface stator 50 has a plurality of peripherally spaced axially-extending, shallow grooves 52 which are essentially rectangular in cross section (FIG. 2) and which confront and are approximately coextensive with the grooves 36 in rotor 35. The number of grooves 52 is preferably one more or one less than the number of grooves 36. At the front end of each of the grooves 52 there is a circular aperture 53 drilled through the stator. Each groove 52 on the exterior of the stator 50 is thus placed in communication with the interior of the stator.

The stator 50 is integral with a cover plate 55. This cover plate is secured by a plurality of threaded studs 56 and wing nuts 57 to the front end of a cup-shaped housing 60.

The housing 60 contains impeller 31, rotor 35, stator 50, and disc 43, which are disposed coaxially. Its rear end wall 62 has a central opening through which the shaft 15 extends into the housing; and it has an integral collar portion 63 by which the housing is centered in a circular opening provided in the front wall 64 of a supporting member 65. Housing 60 is secured to the front wall of supporting member 65 by the threaded studs 66 and winged nuts 67. Supporting member 65 is bolted or otherwise secured to the front face of the housing of motor 10 to be supported thereby.

The cover plate 55 has a collar portion 68 integral therewith and projecting forwardly therefrom. Its bore 69 provides an inlet through which the fluid that is to be homogenized or emulsified can enter the housing. It is externally threaded, as denoted at 70, for coupling it to piping through which the fluid is delivered to the homogenizing unit. Upon the rotation of impeller 31, the fluid is drawn through apertures 53 in stator 50, and forced down the thin axially extending annular passage 75 between grooves 52 and 36, out of the apertures 37 in rotor 35 into the annular space 72 between the outer surface of rotor 35 and the confronting inside face of the side wall of the housing 60, into grooves 32 of impeller 31, and finally out of the housing 60 through a port or duct 73 in the annular side wall of the housing and the bore of an externally threaded collar 74 which is integral with the housing 60. As the fluid passes down the annular passage 75 the rotating edges of the grooves 36 cooperate with the stationary edges of the grooves 52 on the outer peripheral surface of stator 50 to positively shear the particles carried in the fluid which is being pumped. In addition to this positive shearing caused by cooperating edges of the grooves 36 and 52, the particles in the liquid passing between the rotor 35 and stator 50 are also subjected to an implosion phenomenon resulting from the cavitation effect produced when the rotor is operated at a high speed relative to the stator. The high speed creates an energy level of ultrasonic sound waves measurable in kilocycles per second. A suitable sound energy level, or frequency for a particular type of particle, i.e., a frequency at which the dispersion or reduction of particle sizes is at an optimum, may be achieved by varying the rotor speed, and/or, the number of grooves disposed about the confronting peripheral surfaces of the rotor and stator respectively. As a general rule this energy level has been found to be most effective when held within the range of 2.2 to 27.6 kilocycles per second.

By forcing the particles in the fluid to travel through the space 75 from one end thereto to the other, all of the particles are exposed to the shearing edges of grooves 36 and 52 essentially at all times during their passage axially through the pump housing. The time during which a respective particle is subjected to a positive shearing action is thus maintained at a maximum for a given flow rate of fluid through the unit. Moreover, apertures 53, and to a lesser extent apertures 37, tend to cause a reduction in particle size as a result of compressive forces exerted upon the particles as they are forced through these respective apertures.

Since as a general rule the motor 10 is operated at a constant speed, the number of shearing actions to which a particle is subjected during its passage through housing 60 will be inversely proportional to the rate of flow of fluid through the housing. The fluid flow rate is readily controlled by positioning a valve cock or the like at the outlet end 74 of the housing. By throttling the valve the rate of flow of fluid through housing 60 is decreased, thus increasing the number of shearing actions to which a particle will be submitted during its passage through the housing. Conversely, as the valve opening is increased, the rate of flow of fluid through the housing increases

thereby passing a respective particle through the housing more rapidly so that it is subjected to a lesser number of shearing actions during its passage therethrough.

From FIG. 1 it will be noted that the annular flange 43 prevents the incoming fluid from by-passing the apertures 53 in stator 50 and flowing directly from the open rear end of the latter through the adjacent apertures 37 in rotor 35. Moreover, apertures 53 are aligned in a circular path opposite the ends of grooves 36 remote from impeller 31, while the apertures 37 are aligned with the terminal ends of grooves 52 remote from cover plate 55. The fluid is thus forced to flow axially through annular passage 75 as it passes through pump housing 60.

The housing 60 is readily removable for cleaning, re-pairing, or for the replacement thereof by a similar housing containing different homogenizing elements. Leakage of the fluid along shaft 15 out of the housing 60 is prevented by a sealing disc 80 which is seated in a counter-bore in the rear wall 62 of the housing and which is held in place by a coiled compression spring 81 that is interposed between the disc and the shoulder 82 formed at the juncture of part 16 of the shaft and the first reduced diameter portion 21 thereof.

In order to remove the homogenizing unit from the motor 10 the screws 17 are unthreaded. The bore 83 in end wall 64 of supporting member 65 has a diameter great enough for the enlarged end of shaft 15 to pass freely therethrough. At diametrically opposite sides, supporting member 65 has openings 85 therein which permit access to screws 17 and nuts 67.

A modified form of the invention is illustrated in FIGS. 3 and 4. It is recommended when it is desirable to have a preliminary mixing of the fluid before shearing the particles thereof. The modified device is identical to that shown in FIGS. 1 and 2 with the exception that the retaining sleeve 41 and its integral disc 43 are replaced by an inner rotor designated generally at 140. Since with the exception of rotor 140, the elements employed in the modification shown in FIGS. 3 and 4 are identical to the elements employed in the embodiment illustrated in FIGS. 1 and 2, only portions of the pump housing are illustrated in FIG. 3. Identical parts are identified by identical reference numerals in all the figures.

The rotor 140, which is cup-shaped, has an annular wall 141 and is closed at one end by an axially bored end wall 142 which has an internally threaded hub portion 145 extending forwardly therefrom. Rotor 140 also has an annular flange or collar 146 extending axially rearwardly from its bottom 142. The annular wall 141 of the rotor 140 has an outside diameter slightly less than the inside diameter of stator 50, and an axial length slightly less than the axial length of rotor 35. Rotor 140 is disposed concentrically within stator 50 with its open end facing cover plate 55. Its hub portion 145 is threaded onto shaft 15 so that collar 146 on the rotor 140 abuts the impeller 31 to seat the impeller against the shoulder 23 of the shaft.

The annular wall portion 141 of rotor 140 has a plurality of peripherally spaced, axially extending slots 147 intermediate the ends thereof. Slots 147 extend substantially the full length of the annular wall portion of the rotor. The sides of each slot extend parallel to one another and lie in planes offset from the axis of the rotor. They are preferably disposed to be inclined in a direction opposite to the direction (arrow 150 in FIG. 4) of rotation of the rotor. Preferably the rotor has a different number (for instance, twenty-four) of slots from those in stator 50 and rotor 35.

With this second embodiment of the invention, upon entering the housing 60 through cover plate 55, fluid first passes through the slots 147 of the rotor 140 before passing through apertures 53 in stator 50. It then flows through the axially extending annular passage 75 and out apertures 37 in rotor 35 to the outlet side of the pump. The inclined rotor slots 147 tend not only to constantly

blend or mix the fluid, but also impart a slight centrifugal pumping effect to the fluid thereby more readily to urge the fluid and the particles therein through the circular apertures 53 in the stator 50. The operation which takes place in this second described unit is thus essentially a two stage operation, the first being a mixing stage when the fluid is exposed to rotor 140; and the second a particle shearing stage when the fluid passes down passage 75 between the closely adjacent, confronting, grooved faces of the stator 50 and of the rotor 35. As in the case of the annular flange 43 in the embodiment illustrated in FIGS. 1 and 2, the transversely disposed end wall or bottom 142 of the rotor 140 prevents incoming fluid from bypassing the apertures 53 in stator 50.

By restricting the flow of fluid so that it must pass from a point adjacent the inlet end of the unit (as defined by the circular path of apertures 53), axially through the particle shearing area, as defined by the annular space 75 between the stator and outer rotor, before being permitted to pass out of the pump housing, it will be apparent that applicant has provided a novel homogenizing or emulsifying unit in which the most efficient use is made of the shearing elements contained in the unit. In addition, by incorporating centrifugal pumping means along with the blending and shearing means in the unit housing, applicant has provided a continuous flow homogenizing or emulsifying unit which tends to eliminate undesirable temperature rises in the fluid during the processing thereof by the unit, and wherein the rate of flow of fluid through the unit is readily controlled by means of a valve at the outlet end of the unit rather than by altering the speed of rotation of the pumping element itself.

While the invention has been described in connection with two specific embodiments thereof, it will be understood that it is capable of further modification, and this application is intended to cover any variations, uses, or adaptations of the invention following, in general, the principles of the invention and including such departures from the present disclosure as come within known or customary practice in the art to which the invention pertains and as may be applied to the essential features hereinbefore set forth, and as fall within the scope of the invention or the limits of the appended claims.

Having thus described my invention, what I claim is:

1. Homogenizing apparatus comprising a housing having a chamber therein, rotary means in said chamber for pumping fluid therethrough from an inlet adjacent one end of said chamber to an outlet adjacent the opposite end thereof, at least two tubular elements nested in spaced, coaxial relation one within the other in said chamber and defining therebetween an annular passage extending axially of said chamber, the confronting peripheral surfaces of said tubular elements having peripherally spaced, axially extending grooves therein, the grooves in one of said surfaces being essentially coextensive with the grooves in the other of said surfaces, the inner tubular element having a plurality of peripherally spaced apertures therethrough adjacent one end only thereof, and the outer tubular element having a plurality of peripherally spaced apertures therethrough adjacent the opposite end only thereof, each of the apertures in said inner element communicating with one of the grooves in said inner element, and each of the apertures in said outer element communicating with one of the grooves in said outer element, means in said chamber operative to guide incoming fluid through the apertures in said inner element, so that the fluid will flow axially along said annular passage and out of the apertures in said outer element, and one of said tubular elements being operatively connected to said pumping means to rotate therewith relative to the other of said elements, whereby the edges of the grooves in said inner and said outer elements, respectively, cooperate to shear therebetween the fluid carried through said passage.

2. Homogenizing apparatus comprising a casing having a chamber therein, said casing having an inlet and an outlet for admitting fluid to and from said chamber, respectively, homogenizing means in said chamber including a first annular element extending between said inlet and said outlet, a second annular element extending between said inlet and said outlet, and disposed in confronting, radially spaced coaxial relation about said first annular element, particle shearing means disposed on the outer peripheral surface of said first annular element and the inner peripheral surface of said second annular element, respectively, said first annular element having at one end only thereof a plurality of radially extending apertures which are disposed adjacent said inlet, and said second annular element having a plurality of radially-extending apertures which are disposed at the end thereof only which is distal from said one end of said first annular element and which is adjacent said outlet, guide means in said chamber operative to direct incoming fluid into the apertures of said first annular element, whereby during its passage through said casing said fluid is caused to pass successively through the apertures in said first annular element axially along the space between said particle shearing means on said first and second annular elements, respectively, and through the apertures in said second annular element to said outlet.

3. Apparatus as defined in claim 2 wherein said particle shearing means comprise a plurality of peripherally spaced, axially extending grooves in the outer peripheral surface of said first annular element and in the inner peripheral surface of said second annular element, respectively, each of the grooves on said first annular element communicating at one end thereof with one of the apertures in said first annular element, and each of the grooves in said second annular element communicating at one end thereof with one of the apertures in said second annular element.

4. Apparatus as defined in claim 2 wherein said guide means includes a rotary deflecting member positioned coaxially in said first annular element intermediate the ends thereof and having a plane surface extending transversely to the axis of said first annular element and having a diameter slightly less than the internal diameter of said first annular element, and means for mounting said second annular element and said guide means in said chamber for rotation relative to said first annular element.

5. Apparatus as defined in claim 4 wherein the plane surface of said rotary deflecting means is positioned adjacent the end of said first annular element which is remote from said inlet, said rotary deflecting means has an annular wall integral with and extending forwardly from said plane surface toward said inlet coaxially of said first annular element, and said annular wall has a plurality of peripherally spaced, axially extending slots therein operative upon rotation of said deflecting means to subject the incoming fluid to a blending operation before passage of said fluid radially outwardly through the apertures in said first annular element.

6. Homogenizing apparatus comprising a casing having a chamber therein, an inlet and an outlet in said casing adjacent opposite ends of said chamber, respectively, for flow of fluid into and from said chamber, coaxial annular homogenizing elements nested in spaced, coaxial relation relative to one another in said chamber, particle shearing means on the confronting peripheral surfaces of at least two of said elements, the shearing means on one of said peripheral surfaces being substantially axially coextensive with the shearing means on the confronting surface of the next adjacent element, said spaced, confronting shearing means defining therebetween an annular passage intermediate the inlet and outlet in said casing, each of said two elements having therethrough a plurality of circumferentially spaced radial openings, which are arranged in a circular path adjacent one end only of a respective element, the openings in one of said two elements being positioned adjacent one end of said passage, and the openings

in the other of said two elements being positioned adjacent the opposite end of said passage, means in said chamber for guiding fluid from said inlet to the openings in said one element, whereby the incoming fluid passes into said one end of said annular passage and axially thereof to the openings in said other of said two elements, and then to the outlet in said casing, and means in said chamber for rotating said confronting shearing surfaces relative to one another to shear therebetween the fluid carried through said passage.

7. Homogenizing apparatus comprising a housing, having a fluid inlet at one end thereof and a fluid outlet adjacent the other end thereof, a rotary pumping member mounted in said housing adjacent the outlet end thereof, an annular shearing element secured to said pumping member to rotate therewith, a coaxial annular shearing element fixedly secured to said housing, said shearing elements having confronting peripheral surfaces which define a longitudinal passage between said elements, said elements having confronting longitudinal grooves in their confronting peripheral surfaces whose edges constitute shearing edges, one of said shearing elements having adjacent one end only thereof a plurality of circumferentially spaced holes extending radially through it adjacent said

5 inlet and communicating with its grooves to conduct fluid entering said housing into said grooves, and the other of said shearing elements having adjacent one end only thereof a plurality of circumferentially spaced holes extending radially through it adjacent said outlet and communicating with its grooves to conduct fluid from said grooves to said outlet, and means for rotating said pumping member and the element secured thereto to pump fluid from said inlet through the holes in said one element, along said passage, out the holes in said other element and out said

10 outlet.
